United States Patent Office.

CHRISTIAN SHARPS, OF PHILADELPHIA, PENNSYLVANIA.

Letters Patent No. 95,150, dated September 21, 1869.

IMPROVEMENT IN PROPELLERS.

The Schedule referred to in these Letters Patent and making part of the same.

To all whom it may concern:

Be it known that I, CHRISTIAN SHARPS, of Philadelphia, Pennsylvania, have invented certain Improvements in Propellers; and I do hereby declare the following to be a full, clear, and exact description of the same.

My invention relates, for the most part, to improvements in propellers and vessels, for which Letters Patent were granted to me on the 25th day of May, 1869, my present improvements consisting of a device, described hereafter, for resisting the strain to which the inclined shaft, described in the said patent, is subjected; also, of a peculiar manner, described hereafter, of constructing propellers, with a view to lightness and economy.

In order to enable others skilled in the art to make and apply my invention, I will now proceed to describe its construction and operation, reference being had to the accompanying drawing, which forms a part of this specification, and in which—

Figure 1 is a plan view of the stern of a steam vessel, with my improvement.

Figure 2, an end view of the propeller, partly in section.

The shaft A of the propeller is inclined, as in my former patent, and there is in the deck an inclined opening, a, for receiving the propeller.

To the shaft A is secured the hollow hub B, of cast-iron, which, in the present instance, is made six-sided, to correspond with the number of the blades. On each of these six sides is cast a projection or flange, b, so inclined as to correspond with the desired inclination of the blades. These flanges are also made hollow, for the sake of lightness.

Each blade D consists of three plates, d, e, and f, of sheet-iron, the plate d projecting a short distance

between the plates e and f, and the whole being secured together at h, while the plates e and f diverge at this point toward the hub B, where one of the inclined flanges fits between them, the plates being properly secured to the hub by bolts or rivets.

By this arrangement, a large and light blade may be made of comparatively small pieces of sheet-iron, while sufficient rigidity is secured by the diverging plates e and f, which may be secured together by cross-stays, at suitable intervals.

Owing to the peculiar inclined position of the shaft A, in respect to the direction in which the blades act on the water, there must be a constant strain on the shaft, in the direction of the arrow, fig. 1, and consequently a great pressure of the shaft against its bearings i i. In order to resist this strain, I secure to the edge j of the inclined opening a, in the deck, a bracket, E, carrying a roller, k, against the periphery of which the bevelled front end of the hub bears, as shown in fig. 1.

I claim as my invention, and desire to secure by Letters Patent—

1. In combination with an inclined propeller-shaft, A, a roller, k, for resisting the strain imparted to the said shaft, as set forth.

2. A blade, D, composed of three plates, connected together, and secured to a flange on the hub, as set forth.

3. The hollow hub B, with its hollow projections b.

In testimony whereof, I have signed my name to this specification, in the presence of two subscribing witnesses.

CHRISTIAN SHARPS.
